UNITED STATES PATENT OFFICE.

LOUIS ETHELBERT WOODARD, OF CINCINNATI, OHIO.

METHOD AND MEANS FOR PRINTING.

1,406,132.

Specification of Letters Patent. Patented Feb. 7, 1922.

Application filed June 14, 1921. Serial No. 477,366.

To all whom it may concern:

Be it known that I, LOUIS E. WOODARD, a citizen of the United States, and a resident of Cincinnati, in the county of Hamilton 5 and State of Ohio, have invented a new and Improved Method and Means for Printing, of which the following is a description.

My invention is more particularly intended for the printing of theater tickets 10 and has special reference to the printing of a coupon or reserve seat ticket.

The general object of my invention is to provide an economical method of printing the successively numbered tickets to differentiate 15 reserve seat tickets, by means of a cylindrical printing plate composed of half sections produced by setting up the type in separate chases or other forms with parallel lines, the matter in the lines of one chase 20 running continuously with the corresponding lines in the other chase, and forming semi-circular matrices, the plates formed from which, when assembled in cylindrical form, will present the printing elements in 25 the form of a continuous spiral.

The nature of the invention and its distinctive features and advantages, will clearly appear as the description proceeds.

Reference is to be had to the accompanying 30 drawings forming a part of this specification, it being understood that the drawings are merely illustrative of one example of the invention.

Figure 1 is a plan view of a chase having 35 one-half of the type to be printed locked therein;

Figure 2 is a similar view of another chase employed in coaction with the first chase;

Figure 3 is a side elevation of a cylindrical 40 printing plate formed in accordance with my invention.

In carrying out my invention, in practice, I take two chases as indicated at A, A', and I set up therein the matter to be printed, said matter being on parallel lines and the lines preferably being oblique. The matter in the lines of one chase is continuous with the matter in the corresponding lines of the other chase. Thus, the matter set up in the 45 first line of chase A' is continued to the first line of the chase A as at 10 to the full width of the latter, then a second line in the chase A' is completed and the set-up matter continued to the second line of the second chase 50 A. Thereby, the first line 10 for example in the chase A will be continuous with the

matter in the first line 10^a of the chase A' and so on throughout the successive lines in the respective chases.

The matter having been imposed (or set 60 up) in the respective chases and locked, I produce matrices from the respective forms. If the lines in the chases are oblique, the lines in the matrices will necessarily be also 65 oblique but a similar result can be obtained by having the lines in the chases parallel with the top and bottom thereof, the flongs for the matrices in this case being imposed on the chases or forms at such an angle that the lines will be produced obliquely in the 70 matrices.

The matrices having been produced with the lines of printing matter oblique therein, semi-circular printing plates are cast therefrom. With the semi-circular printing 75 plates having lines 11, 11^a corresponding with the lines of the matrices produced from the flongs, the lines in the cylindrical plate will form a continuous spiral.

The described cylindrical printing plate 80 is employed in a press provided with means to shift the cylinder endwise as it revolves through the medium of a screw arrangement having the same pitch as the pitch of the spirally disposed printing elements on the 85 cylinder plate.

In practice, the paper or cardboard to be printed is fed from a roll and passed between the cylinder and an impression device, thus impressing the type matter on the 90 printing stock. In the case of theater tickets, the first seat designation will be printed, the stock advanced the length of the ticket, and the second seat designation impressed, and so on to the extent desired. It 95 is to be understood that the type matter in the plates may be arranged to print the body and date of the ticket as well as the reserve seat designation. The ticket printing being completed, the printed strip or ribbon is 100 now advanced to a revolving knife or cutter in a manner well known in printing, to cut it into proper lengths.

Since various colored tickets are desired for a theater to differentiate the various sections of seats, a roll of stock of each color 105 will be provided in practice, each with separate printing mechanism. Thus, if ten colors are to be printed at one time from the above described impression cylinder, ten 110 separate printing devices for the body and date will be arranged side by side. As the

cylinder revolves and advances the various mechanisms will be started for printing and stopped when the desired number of tickets is printed, the starting and stoppage being 5 brought about by a trip finger or trigger coming in contact with a lug or trip on the impression cylinder.

I would state in conclusion that while the 10 illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:—

1. The method of producing a printing medium, consisting in imposing the type 20 matter in two chases on oblique lines, the lines of matter in the one chase being continuous with the corresponding lines of the other chase, forming semi-cylindrical matrices of the matter in said chases, and producing a cylindrical printing plate from said matrices.

2. In the method of producing a printing medium, the steps of forming two separate type assemblages of the matter to be printed 30 with the lines of matter parallel and with

the matter in one assemblage continuous with the matter in the corresponding lines of the other assemblage, and forming matrices from said type assemblages with the lines of the matter in the matrices running 35 obliquely to constitute a continuous spiral when the matrices are assembled in cylindrical form.

3. In the method of producing a printing medium, the steps of forming two separate 40 type assemblages of the matter to be printed with the lines of matter parallel and with the matter in the lines of one assemblage continuous with the matter in the corresponding lines of the other assemblage, 45 forming semi-cylindrical matrices from said type assemblages with the lines of matter in the matrices running obliquely to constitute a continuous spiral when the matrices are assembled in cylindrical form, and producing cylindrically arranged printing plates from said matrices.

4. A matrix formed of two semi-cylindrical sections having the matter impressed therein disposed on oblique lines, the lines 50 of one section registering with those of the other section to produce a continuous spiral line when said sections are juxtaposed to form a cylinder.

LOUIS ETHELBERT WOODARD.
